RAILWAY CAR-END BUFFER

George E. Dath, Mokena, Ill., assignor to W. H. Miner, Inc., Chicago, Ill., a corporation of Delaware

Application November 15, 1944, Serial No. 563,493

7 Claims. (Cl. 213—221)

1

This invention relates to improvements in buffers for railway cars.

One object of the invention is to provide a simple and efficient buffer mechanism for railway cars having combined spring and frictional resistance for absorbing the shocks to which the car is subjected, wherein the frictional resistance is substantially constant throughout the compression stroke of the mechanism.

A more specific object of the invention is to provide a buffer housing secured to the end of the car, a buffer head slidingly telescoped within the housing, spring means yieldingly opposing inward movement of the buffer head with respect to the housing, and means for providing substantially uniform frictional resistance to inward movement of the buffering head during the entire compression of the mechanism, wherein the friction means comprises friction shoes movable with the buffer head and in sliding contact with the interior of the housing.

Other objects of the invention will more clearly appear from the description and claims hereinafter following.

In the drawing forming a part of this specification, Figure 1 is a longitudinal, vertical sectional view of my improved buffer mechanism illustrating the same mounted in position on the end of a railway car. Figure 2 is a transverse, vertical sectional view, corresponding substantially to the line 2—2 of Figure 1. Figure 3 is a side elevational view of the buffer head employed in my improved mechanism, detached from the other parts of the same.

In said drawing, 10 indicates the end wall of a railway car, the portion illustrated being at one side of the longitudinal center line of the car and having my improved buffer mechanism mounted thereon. As will be understood by those skilled in this art, the buffer mechanism is duplicated at the other side of the car and the two mechanisms cooperate in a well-known manner with a pair of similar buffer mechanisms on the end of an adjacent car.

My improved buffer mechanism proper, as shown in the drawing, comprises broadly a housing A secured to the end of the car; a buffer head B slidingly telescoped within the housing; a buffer spring C; friction shoes D—D—D in sliding frictional engagement with the housing; a wedge E for holding the shoes spread apart; a spring element F yieldingly pressing the shoes against the wedge E; and a retainer bolt G for holding the mechanism assembled.

The housing A is in the form of a substantially

2

tubular casting of hexagonal, transverse cross section having a vertical, transverse end wall 11 closing the rear end thereof. The end wall 11 is laterally extended outwardly beyond the housing, thereby providing flanges 12—12 for securing the housing to the end wall of the car. The housing is mounted on the end wall of the car and is secured thereto by any well-known securing elements, such as bolts 13—13 and 13—13 extending through openings in the flanges 12—12 and the end wall 10 of the car. The wall 11 of the housing A has an inwardly extending, central, hollow boss 14 which serves to center the buffer spring C and also serves as an anchorage for the retainer bolt G. At the forward end, the housing A is open and the walls thereof are inwardly thickened, as indicated at 15. The thickened wall portion 15 presents three V-shaped, interior friction surfaces 16—16—16, which are parallel to the central longitudinal axis of the mechanism.

The buffer head B includes a tubular shell 17 of hexagonal, transverse cross section, extending rearwardly from the buffer head proper 18, which is in the form of a front wall closing the forward end of the tubular shell 17. The wall 18, which forms the buffer head proper, is extended laterally outwardly beyond the shell 17 and has a convex outer face which is usual in devices of this kind. The shell 17 is provided with three rectangular openings 19—19—19 through the side walls thereof, which accommodate the friction shoes D—D—D, as hereinafter pointed out. Rearwardly of the openings 19—19—19, the shell has three interior, inwardly projecting retaining lugs 20—20—20, which are equally spaced circumferentially of the shell.

The wedge E is in the form of a hollow block provided with a rearwardly extending, central, hollow boss 21. The rear end of the wedge E thus presents an annular abutment shoulder 22. At the forward end, the wedge E is provided with three wedge faces 23 of V-shaped, transverse cross section, which converge forwardly and inwardly toward the central longitudinal axis of the mechanism. At the inner ends of the wedge faces 23, the wedge is provided with three radially outwardly projecting retaining lugs 24—24—24, which are respectively engaged in front of the lugs 20—20—20 of the shell 17 of the buffer head B, thereby holding the wedge against inward or rearward movement with respect to the buffer head.

The friction shoes D are three in number and are in the form of solid blocks. Each shoe is provided with a longitudinally extending friction

surface 25 of V-shaped, transverse cross section on the outer side thereof. The friction shoes D—D—D are disposed within the tubular shell 17 of the buffer head B and project through the openings 19—19—19 of said sleeve and have the V-shaped friction surfaces thereof respectively engaging the V-shaped friction surfaces 16—16—16 of the housing A. On the inner side, at the rear end thereof, each shoe has a wedge face 26 of V-shaped, transverse cross section engaging the corresponding wedge face 23 of the wedge E.

The spring F is in the form of a light helical coil, which is under initial compression and is disposed within the shell 17 and has its front and rear ends bearing respectively on the end wall 18 of the sleeve and the front ends of the friction shoes D—D—D.

The buffer spring C is in the form of a heavy helical coil, which is disposed within the housing A. The spring C bears at its front end on the lugs 20—20—20 of the shell 17 and on the inner end of the wedge E, that is, on the annular abutment shoulder 22 thereof. The rear end of the spring C bears on the vertical rear wall 11 of the housing A, and is centered by the boss 14 of the housing.

The retainer bolt G anchors the wedge E to the housing A, having its head seated in the hollow boss 21 of the wedge and the nut thereof seated in the hollow boss 14 of the housing A.

In assembling the mechanism, the spring F, the shoes D—D—D, and the wedge E, with the bolt G attached thereto, are first assembled within the shell 17 of the buffer head B, the bolt being attached to the wedge E by entering the shank of the same through the opening 27 provided in the front end of the wedge for this purpose. The wedge is interlocked with the buffer head B by engaging the lugs 24 thereof in front of the lugs 20 of the buffer head. As will be evident, the shoes D—D—D may be spread apart during this operation of assembling the wedge with the buffer head, inasmuch as the shoes are free to move laterally outwardly through the openings 19—19—19 of the shell 17. After the parts have been thus far assembled, a clamp in the form of a band or other suitable means, which surrounds the shoes, is applied to press the shoes inwardly so that the assembled unit may be telescoped within the housing A. The spring C is then placed within the housing A and the assembled unit, comprising the head B, the spring F, the shoes D—D—D, the wedge E, and the bolt G are telescoped within the housing A. The mechanism is then compressed and the nut applied to the retainer bolt G.

The operation of my improved buffer mechanism is as follows: Upon inward movement of the buffer head B through pressure exerted thereon by any object, such as the buffer head of an adjacent car, the friction shoes are forced inwardly of the housing A with the buffer head, thereby providing frictional resistance as the shoes slide inwardly on the friction surfaces 16—16—16. Inasmuch as the spring F is under initial compression, the frictional resistance provided remains substantially constant during the entire compression stroke. Inward movement of the buffer head is yieldingly resisted by the buffer spring C, which reacts between the housing A and the lugs 20—20—20 of the shell 17 of the buffer head B and also reacts between the housing A and the wedge E. Inward movement of the buffer head B is limited by engagement of the head proper 18 thereof with the front end of the

housing A. When the actuating force is removed, the spring C returns all of the parts to the normal full release position shown in Figure 1, outward movement of the wedge E being limited by the retainer bolt G and outward movement of the buffer head B, in turn, being limited by engagement of the lugs 24 of the wedge with the lugs 20 of the buffer head.

I have herein shown and described what I now consider the preferred manner of carrying out my invention, but the same is merely illustrative and I contemplate all changes and modifications that come within the scope of the claims appended hereto.

I claim:

1. In a buffer for railway cars, the combination with a housing secured to the end of the car; of a buffer head slidably telescoped within said housing; an expandable friction clutch carried by said buffer head and having sliding frictional engagement with the interior walls of the housing, said clutch including friction shoes having direct shouldered engagement at their outer ends with the buffer head to be moved inwardly thereby, and a spreading wedge member engaging said shoes; spring means under constant uniform compression reacting between the buffer head and shoes for pressing the same against the wedge member and holding said clutch expanded; and spring means yieldingly opposing movement of the buffer head and wedge inwardly of the housing.

2. In a buffer for railway cars, the combination with a housing secured to the end of the car, said housing having interior friction surfaces extending lengthwise of the same; of a buffer head slidably telescoped within the housing, said buffer head having a stop shoulder thereon; friction shoes movable with the buffer head and having sliding engagement with the interior friction surfaces of the housing; a separate wedge member shouldered on the forward side of the shoulder of the buffer head to hold said wedge member against inward movement with respect to the buffer head, said wedge member having wedging engagement with the shoes; a spring under initial compression reacting between said buffer head and shoes to press the latter against the wedge member; and a second spring bearing on the rear of said shoulder of the buffer head yieldingly opposing movement of the buffer head and wedge member inwardly of the housing.

3. In a buffer for railway cars, the combination with a housing secured to the end of the car, said housing having longitudinally extending, interior friction surfaces; of a buffer head slidably telescoped within the housing; friction shoes movable in unison with said buffer head and slidably engaging the friction surfaces of the housing; retaining lugs at the inner end of said head; a wedge block interposed between said shoes and lugs of the buffer head and seated against the forward sides of said lugs, said wedge having wedging engagement with the shoes; a spring reacting between the buffer head and shoes for forcing the latter against the wedge; and a second spring yieldingly opposing movement of the buffer head inwardly of the housing.

4. In a buffer for railway cars, the combination with a housing having longitudinally extending, interior friction surfaces; of a buffer head movable toward and away from said housing, said head including a rearwardly extending sleeve integral therewith and slidably telescoped within the housing; a plurality of friction shoes carried by said sleeve and extending through

the walls thereof and having sliding frictional engagement with the friction surfaces of the housing; interior stop lugs on said sleeve rearwardly of said shoes; a central wedge block interposed between said shoes and stop lugs and having shouldered engagement with the lugs, said wedge block and shoes having interengaging wedge faces; spring means under predetermined initial compression within said sleeve reacting between said buffer head and shoes for forcing the latter against said wedge; and a spring opposing movement of the buffer head inwardly of the housing.

5. In a buffer for railway cars, the combination with a housing secured to the end of the car, said housing having lengthwise extending, interior friction surfaces; of a buffer head including a buffer plate and a tubular sleeve extending rearwardly from said plate, said sleeve being slidably telescoped within the housing; a plurality of laterally inwardly projecting, interior, retaining lugs at the rear end portion of said sleeve; a wedge block having a plurality of laterally outwardly projecting retaining lugs shouldered against the forward sides of said first named retaining lugs; wedge faces at the forward end of said wedge block; a plurality of friction shoes within said sleeve, said shoes having wedge faces at their rear ends engaging the wedge faces of the wedge, said shoes projecting through the side walls of said sleeve and having outer friction surfaces engaging the interior friction surfaces of the housing; a spring under initial compression within said sleeve interposed between the buffer plate and said shoes and bearing at opposite ends on said plate and shoes; and a spring within said housing yieldingly opposing inward movement of the buffer head, the front end of said last named spring bearing on the retaining lugs of the sleeve and the inner side of said wedge.

6. In a buffer for railway cars, the combination with a housing secured to the end of the car, said housing having an interior friction sur-

face; of a buffer head slidably telescoped within the housing; a wedge block having shouldered engagement with the buffer head to hold said wedge block against movement rearwardly of the head; a friction shoe carried by said buffer head in wedging engagement with the block and in sliding frictional engagement with the interior friction surface of the housing; means reacting between the buffer head and shoe for yieldingly forcing the shoe against said wedge block; means yieldingly opposing inward movement of the buffer head with respect to the housing; and a retainer bolt anchored to the housing and wedge for limiting outward movement of the wedge with respect to the housing.

15 7. In a buffer for railway cars, the combination with a housing secured to the end of the car, said housing having longitudinally extending, interior friction surfaces; of a buffer head slidably telescoped within the housing; friction shoes movable in unison with said buffer head and slidably engaging the friction surfaces of the housing; retaining lugs at the inner end of said head; a wedge block interposed between said shoes and lugs of the buffer head and seated against the forward sides of said lugs, said wedge having wedging engagement with the shoes; a spring reacting between the buffer head and shoes for forcing the latter against the wedge; a second spring yieldingly opposing movement of the buffer head inwardly of the housing; and a retainer bolt for holding said buffer head assembled with the housing, said bolt being anchored at its inner end to the housing and at its outer end to the wedge.
